TELEVISION CABINET

Carl W. Sundberg, Bloomfield Hills, Mich., assignor to Sylvania Electric Products Inc., a corporation of Massachusetts

Application January 6, 1958, Serial No. 49,143

Term of patent 14 years

(Cl. D56—4)

Fig. 1

Fig. 2

Fig. 1 is a front perspective view of a television cabinet showing my new design; and

Fig. 2 is a side perspective view of the design shown in Fig. 1.

The dominant features of my design reside in the portions shown in full lines.

I claim:

The ornamental design for a television cabinet, as shown and described.
